United States Patent Office

Des. 197,020
Patented Dec. 3, 1963

197,020

TRAY OR SIMILAR ARTICLE

Philip Zeiler, 3770 Sierra Drive, Honolulu, Hawaii

Filed Oct. 25, 1961, Ser. No. 67,294

Term of patent 14 years

(Cl. D44—10)

FIG. 1 is an end elevational view of a tray or similar article, showing my new design;

FIG. 2 is a side elevation of the same; and
FIG. 3 is a top plan view of the same.

I claim:

The ornamental design for a tray or similar article, as shown.
